UNITED STATES PATENT OFFICE.

FRANCIS P. GSTALDER, OF CLEVELAND, OHIO.

SIGN.

Application filed March 3, 1927. Serial No. 172,452.

The present invention relates to improvements in signs primarily intended for use as road and street guides, and the primary object of the invention is to provide a sign 5 of this character embodying interchangeable letters or other indicating characters which are readily interchangeable for displaying of the desired information.

A further object of the invention resides 10 in the provision of an interchangeable sign as set forth, wherein the letters or other indicia are capable of being easily assembled in the desired form, and which sign is of a character to remain in good condition for 15 an indefinite length of time and not be rendered illegible by excessive accumulation of dust and dirt upon the sign.

A further object of the invention resides in the provision of a sign which may be 20 economically constructed from sheet metal, and one wherein a single fastening element serves for locking the letters or characters in their proper assembled form.

Other objects and advantages of the invention 25 will be apparent during the course of the following detailed description, taken in connection with the accompanying drawing forming a part of this specification and in which drawing:

30 Figure 1 is a perspective view of the improved sign showing the same assembled for use and mounted upon a suitable support.

Figure 2 is a perspective view showing 35 the manner of assembling the sign.

Figure 3 is an enlarged face plan view of 40 the sign.

Figure 4 is a longitudinal section on line 4-4 of Figure 3 and showing the manner 45 in which the single fastening element prevents longitudinal movement of the letters or characters when supported in the frame.

Figure 5 is an enlarged transverse section on line 5-5 of Figure 3 and illustrating the 50 manner in which the letters are held against movement out of the supporting frame.

Figure 6 is an enlarged transverse section on line 6-6 of Figure 3 and illustrating the 55 locking arrangement for the outer end of the clamp or lock bar for the letters.

Figure 7 is a fragmentary perspective view of the outer end of the sign frame and showing the manner in which the locking bar is connected with the outer end of the 60 sign rack.

Figure 8 is a perspective view of the clamp

bar before being bent for attachment to the particular type of support upon which the sign is to be mounted.

Referring to the drawing in detail, and 60 wherein similar reference characters designate corresponding parts throughout the several views, the improved sign is shown as embodying a rack or frame A for removably receiving in assembled relation 65 longitudinally therealong letters or other desired characters B, and a clamp or locking bar C for retaining the letters B in assembled relation upon the rack A.

Referring first to the rack A, and which 70 may be readily stamped from suitable gauge sheet metal, the same embodies a substantially L-shaped body portion for providing a vertical back plate 10 having a 75 right angularly extending base flange 11 at its lower edge. An arrow head 12 is preferably provided at the outer end of the back plate 10, and this arrow head is preferably disposed past the outer end of the base flange 11. The outer end of the back 80 plate 10 is provided with a rectangular shaped slot 13 which extends longitudinally of the back plate, while the inner end of the back plate is provided with a suitable aperture 14, the slot 13 and aperture 14 preferably being arranged at the longitudinal center of the back plate. Bent upwardly 85 at a right angle and in spaced relation along the free edge of the base flange 11, is a suitable number of clips or tongues 15 the inner faces of which preferably extend flush 90 with the free edge of the base flange and parallel with the back plate 10. The rack A may be of any suitable length for accommodating the desired number of letters B 95 required to make up the desired sign, without any waste of material, and with the terminally disposed letters spaced inwardly of the slot 13 and aperture 14.

In the example shown, the sign characters 100 B are in the form of letters each being provided with a base plate 16 provided at its lower edge with a forwardly extending clamping flange 17 which preferably extends throughout the length of the base 105 plate and of a width substantially equal to the distance between the confronting faces of the back plate 10 and the clips 15. These base plates 16 are preferably of a height equal to that of the back plate 10, and 110 connect with the lower edges of the letters by means of neck portions 18 so that the

letters are disposed wholly above the upper edge of the rack A. These base plates 16 are also of a length so that when the characters are assembled in proper order, with the plates in abutting relation, the characters proper will be disposed in proper spaced relation longitudinally along the rack A.

The clamp or locking means C for retaining the sign characters B in assembled relation upon the rack A, may also be formed from a strip of metal and embodies a locking bar 20 which is of a length substantially equal to that of the back plate 10, and formed at the outer end of the bar 20 is a right angularly offset T shaped lug 22 the head 23 of which is intended for locking engagement with the rack A upon relative swinging movement of the sections 20 A and C. Provided adjacent the inner end of the straight locking bar 20, is a suitable aperture 24 which when the bar is in a position for retaining the characters B upon the rack A, aligns with the aperture 14 of the rack A. Provided at the inner end of the locking bar 20, and preferably constituting an integral part or continuation thereof, is an attaching portion 25 provided with suitable apertures 26 and 27, the aperture 26 being disposed adjacent the aperture 24 and the aperture 27 preferably being disposed adjacent the free end of the attaching portion.

As will be observed in Figures 1 and 2, the attaching portion 25 has been arcuated for attachment of the sign to a cylindrical support 28, and when desiring to secure the sign to a cylindrical support, a companion attaching portion 29 having terminal openings 30 and 30', cooperates with the attaching portion 25 for attachment of the sign to a cylindrical support as at 28. When applying the sign to a flat surface, the attaching portion is left straight as in Figure 8, and suitable fastening elements passed through the apertures 26 and 27 for attachment of the sign to the support.

In assembling of the sign, the proper sign characters B are first positioned in proper order upon the rack A with the base plates 16 contacting with the back rack plate 10 and the clamping flanges 17 resting upon the rack base flange 11. The clamp C is then disposed at a right angle to the rack A and the head 23 of the T shaped lug 22 inserted through the slot 13 from that side of the back plate from which the base flange 11 extends. The clamp C is then swung downwardly over the face of the sign characters into a parallel position with the back plate 10, with the locking bar 20 moving to a position between the base plates 16 and the clips 15, and with the lower edge of the locking bar engaging the upper surfaces 65 of the clamping flanges 17. As will be ob-

served in Figure 5, the clips 15 cause the locking bar 20 to contact with the base plates 16 for retaining the base plates in contact with the back plate 10 of the rack A. When the bar 20 is moved to a retaining position, the aperture 24 at its inner end aligns with the aperture 14 of the back plate 10, and upon passing a suitable bolt 32 through the aligning apertures 14 and 24, the locking bar is held in a position for retaining the sign characters in assembled relation upon the rack A. As will be observed in Figures 6 and 7, the head 23 will serve to retain the outer end of the locking bar connected with the outer end of the back plate 10 when the locking bar is swung into parallel relation with the back plate.

By again observing Figure 5 it will be seen that the sign characters are held against upward movement by means of the locking bar 20 extending across the upper surface of the clamping flanges 17 of the base plates 16.

When attaching the sign to a cylindrical support as illustrated in Figure 1, the bolt 32 may also be extended through the aperture 30 of the clamping section 29, and upon passing of a suitable bolt as at 35 through the apertures 27 and 30', the sign may be rigidly connected with the support 28.

It is preferred that the T shaped lug 22 when in a locked position, cause the outer end of the locking bar to create a binding action upon the outermost sign character, and that the bolt 32 create a binding action upon the innermost sign character for preventing longitudinal movement of the characters when assembled along the rack A.

While as before stated, it is preferred that the racks A and clamp bar 20 be of different lengths so that selection may be made of a length which accommodates, without any waste of material, the required number of sign characters to make up the sign, such is not entirely essential since the clamping action created by the lug 22 and bolt 32 will clamp the base plate of the terminal characters tight against the back plate 10 for preventing longitudinal movement of the characters.

From the foregoing description it will be apparent that a novel and efficient type of sign has been provided embodying interchangeable sign characters which may be easily arranged in proper order for displaying of the desired information, and which characters are locked in assembled relation by means of a single retaining element.

Changes in detail may be made to the specific form of the invention herein shown and described, without departing from the spirit of the invention or the scope of the following claims.

I claim:

1. A holder for sign characters having a marginal flange at one edge thereof, com-

prising a rack provided at one edge with a base flange upon which the flange of the sign character rests, a locking bar pivotally connected at one end to one end of the rack 5 for clamping of the sign character flange to the base flange of the rack, and means connecting the opposite end of the locking bar to the rack for preventing withdrawal of the sign character from the rack.

10 2. A holder for sign characters provided with base plates, comprising a rack embodying a stiffened back plate, a flexible locking bar pivotally connected at one end to the outer end of the rack for clamping the char-

15 acter base plates to the back plate when the bar is swung into aligning relation with the back plate, and means for retaining the locking bar in binding contact with the base plates of the terminally disposed characters.

20 3. A sign comprising a rack embodying a back plate and a base flange, a plurality of sign characters for assembling on the rack and each embodying a base plate and a clamping flange engageable respectively with 25 the back plate and base flange of the rack, and a removable locking bar for retaining the sign characters in assembled relation with their base plates contacting with the back plate of the rack and their clamping 30 flanges contacting with the base flange of the rack.

4. A sign comprising a rack embodying a back plate and a base flange, a plurality of sign characters each embodying a base plate 35 and a clamping flange for contacting respectively with the back plate and base flange of the rack, a locking bar pivotally and detachably connected at one end with the outer end of the rack and engageable with the base 40 plates and clamping flanges of the characters for retaining the characters in assembled relation upon the rack, and means connecting the inner end of the rack to the inner end of the locking bar for preventing swinging 45 movement of the locking bar out of engagement with the sign characters.

5. A sign comprising a rack embodying a back plate and a forwardly extending base flange, sign characters for assembling on the 50 rack, each including a base plate and a clamping flange for contact with the back plate and base flange respectively of the rack, a locking bar pivotally and detachably connected at one end with the outer end of the 55 rack and movable across the face of the characters into aligning relation with the rack back plate and into engagement with the clamping flanges of the characters, means for connecting the inner end of the locking 60 bar to the inner end of the back plate, and means provided at the inner end of the locking bar for attachment of the sign to a support.

6. A sign comprising a rack embodying a 65 back plate and a forwardly extending base

flange, said back plate having a longitudinally extending slot provided adjacent its outer end, sign characters each including a base plate and a clamping flange engageable respectively with the back plate and base 70 flange of the rack, a locking bar for the characters, provided at its outer end with an offset lug insertible into the slot of the back plate and adapted to interlock therewith when the locking bar is swung parallel with 75 the back plate for retaining of the characters in assembled relation, and means detachably connecting the inner end of the locking bar to the inner end of the rack.

7. A sign comprising a rack embodying a 80 back plate and a base flange having clips provided at its free edge and extending parallel with the back plate, a plurality of sign characters each embodying a base plate and a clamping flange engageable respectively 85 with the back plate and base flange of the rack, a locking bar pivotally and detachably connected at one end with the outer end of the back plate and movable to a position between said clips and base plates of the 90 characters into engagement with the clamping flanges of the characters, a bolt passing through the inner end of the locking bar and back plate for retaining the locking bar in engagement with the clamping flanges of the 95 characters, and means for connecting the locking bar at its inner end to a suitable support.

8. A sign comprising a rack embodying a 100 back plate and a base flange, sign characters for assembling on the rack and each including a base plate and a clamping flange engageable respectively with the back plate and base flange of the rack, and clamping means for the characters including a locking bar 105 pivotally and detachably connected at its outer end to the outer end of the back plate and provided at its inner end with an attaching portion for attachment of the sign to a suitable support, and means connecting 110 the inner end of the locking bar with the inner end of the rack plate for preventing swinging movement of the locking bar out of holding relation with the sign characters.

9. A holder for the interchangeable supporting of sign characters provided with base plates, comprising a rack embodying a back plate and a base flange, said back plate at its outer end being provided with a longitudinally extending slot and having an aperture provided at the inner end of the back plate, said rack serving as a support for the sign characters with the base plate of the characters contacting with the back plate of the rack between the slot and aperture provided respectively at the outer and inner ends of the back plate, a locking bar for the characters having a T shaped lug at its outer end for locking engagement in the slot of the back plate and having an aperture at its in- 130

ner end for aligning with the aperture at the inner end of the back plate, said lug when in locking engagement with the back plate to create a binding action upon the outermost sign character, and a bolt passing through the aligning apertures at the inner end of the locking bar and back plate for re-

taining the bar and plate in assembled relation and for creating a binding action upon the innermost sign character whereby the characters are held against movement longitudinally of the supporting rack.

FRANCIS P. GSTALDER.
